CLAIM

The ornamental design for a cartridge for generating therapeutic foam, as shown and described.

DESCRIPTION

The file of this patent contains at least one drawing executed in color. Copies of this patent with color drawings will be provided by the Office upon request and payment of the necessary fee.

1. Cartridge for generating therapeutic foam

1.1 : Front

1.2 : Back

1.3 : Left

1.4 : Right

1.5 : Top

1.6 : Bottom

1.7 : Perspective

The color shown on the claimed design forms no part thereof.

1 Claim, 7 Drawing Sheets
(5 of 7 Drawing Sheet(s) Filed in Color)

1.3
